Primary Examiner — Angela J Lee(74) *Attorney, Agent, or Firm* — Hayes Soloway P.C.(57) **CLAIM**

The ornamental design for a fire rated downlight housing, as shown and described.

DESCRIPTION

FIG. 1 is a top plan view showing my design;
FIG. 2 is a bottom plan view thereof;
FIG. 3 is a side view from the top;
FIG. 4 is a side view from the bottom;
FIG. 5 is a perspective view thereof from one side, the other side being a mirror image;
FIG. 6 is a top plan view of a second alternative embodiment of my design;
FIG. 7 is a bottom plan view thereof;
FIG. 8 is a side view from the top;
FIG. 9 is a side view from the bottom;
FIG. 10 is a perspective view thereof from one side, the other side being a mirror image;
FIG. 11 is a top plan view of a third alternative embodiment of my design;
FIG. 12 is a bottom plan view thereof;
FIG. 13 is a side view from the top;
FIG. 14 is a side view from the bottom; and,
FIG. 15 is a perspective view thereof from one side, the other side being a mirror image.
The broken lines illustrate environmental components of the fire rated downlight housing which form no part of the claimed design.
